UNITED STATES PATENT OFFICE.

MOSES C. BIGNALL AND GEORGE W. WHITMAN, OF ST. LOUIS, MISSOURI;
SAID WHITMAN ASSIGNOR TO SAID BIGNALL.

PIPE CUTTING AND THREADING MACHINE.

SPECIFICATION forming part of Letters Patent No. 309,374, dated December 16, 1884.

Application filed December 1, 1883. (No model.)

To all whom it may concern:

Be it known that we, MOSES C. BIGNALL and GEORGE W. WHITMAN, both of St. Louis, Missouri, have made a new and useful Improvement in Pipe Cutting and Threading Machines, of which the following is a full, clear, and exact description, reference being had to the annexed drawings, making part of this specification, in which—

10 Figure 1 is a front end elevation of the improved machine, the bed-plate being shown in section, a portion of the machine being broken away to exhibit the interior; Fig. 2, a plan of the parts shown in Fig. 1; Fig. 3, a longitudinal section on the line 3 3 of Fig. 1, the cam-ring being in the position indicated by the dotted bracket, which brings the slots c^1 in line with the dies A; Fig. 4, a longitudinal section on the line 4 4 of Fig. 1, the cam-ring being in the position last stated; Fig. 5, a detail, being a side elevation, partly in section, of the parts immediately connected with the latch; and Fig. 6 a detail, being a top view of a portion of the die-block.

25 The same letters of reference denote the same parts.

This invention has relation to the means for opening and closing the dies and for removing them from the die-block. It also relates 30 to the die-block latch and to various details of the construction.

Saving as modified by the present improvement the machine is of the usual description. The dies A A A, &c., are held in the usual 35 manner in the die-head B, and adapted to be adjusted radially toward and from the center of the die-head, so that the dies can be closed or opened, as desired. The means for operating the dies are as follows: The die-head is held 40 in a cap or box constituting a combined face-plate and cam-ring, C, having a series of cam-surfaces, $c c$, &c., against which the outer ends of the dies A A, &c., respectively abut. The combined face-plate and cam-ring, which is 45 held to the die-head by detachable flanged ring E, is adapted to be rotated in a reciprocating manner upon the die-head. A lever, D, is pivoted at d to a fixed part of the construction, and at d' is jointed to a rod, d^2 , which in

turn is connected with a bracket, c' , that is 50 fastened to the cam-ring C. By turning the lever D upon its pivot, as indicated by the broken lines in Fig. 1, the cam-ring is rotated upon the die-head. When the lever is turned up so as to draw the bracket c' toward the 55 pivot d , the cam-surfaces $c c$, &c., recede from the dies A A, thereby enabling the dies to be opened. The dies A A, &c., are each provided with a stud, a , which, when the die is in place, engages in a slot, c^2 , which is formed in the 60 face-plate portion of ring C parallel with the cam-surface c , as shown in Figs. 1, 3, 4. By reason of this engagement the dies are separated when the combined face-plate and cam-ring is drawn in the direction described; but 65 when the lever D is turned down, as shown in the full lines in Fig. 1, the combined face-plate and cam-ring C is rotated in the opposite direction, and the cam-surfaces are thereby caused to press the dies A A, &c., radially inward into the die-head. The lever D is preferably adjusted to the bracket c' so as to set the dies A A, &c., inward to the exact point desired by means of the nut c^3 , Figs. 1, 2, for 70 which purpose the rod d^2 is suitably threaded 75 to receive the nut c^3 . In this manner the dies A A, &c., can be readily and rapidly closed and expanded as desired. When it is desired to withdraw the dies from the die-head, as when it is desired to change the dies for any 80 purpose, the lever D is turned upward far enough to move the combined face-plate and cam-ring to bring the openings $c^4 c^4$ opposite the dies A A, &c., respectively. These openings $c^4 c^4$ extend radially through the cam-ring 85 and connect, respectively, with the slots $c^2 c^2$, as shown, and when the openings come into coincidence with the dies the dies drop through them. The opening c^4 is of sufficient width, as seen in Fig. 3, for the stud a to pass. So 90 far as this mode of withdrawing the dies from the die-head and cam-ring is concerned the cam-surfaces may or may not be used. The ring E, Figs. 1, 2, 3, 4, is secured to the die-head by means of the fastenings e . It holds 95 the combined face-plate and cam-ring in place. It is also provided with a pointer, e' , Fig. 1, which is used in connection with the gradu-

tion e^2 on the face-plate of the cam-ring. This enables the operator to adjust the cam-ring upon the die-head readily and accurately to the desired point, and thereby close the dies 5 properly upon the pipe I. The die-block F, consisting of the die-head B and combined face-plate and cam-ring C, is hinged at f so that it can swing open in the usual manner. When closed the die-block is fastened by 10 means of the latch G. The block F is provided with the lug f', which, when the block is closed, passes between the lugs h h' upon the die-block-frame H. The latch G is journaled at g to the lug f', and by turning it upon the journal, as 15 shown in the full lines in Fig. 1, its inner end, g', is made to engage in a recess, h', in the lug h, and as long as the latch is in this position the die-block is fastened, and to unfasten it the latch must be turned into the position 20 shown in the broken lines, Fig. 1. The cam-ring C is provided with the projection c³, Figs. 1 and 6, and the frame H is provided with a stop, h³. The projection as the cam-ring is drawn around encounters the stop, and the 25 farther rotation in that direction of the cam-ring is thereby prevented. When it is desired to turn the cam-ring around so as to bring the openings c⁴ c⁵ into coincidence with the dies A A, the stop h³ is turned around in its bearing 30 h⁴ to bring it into the position as shown in the broken lines h⁵. The cam-ring can then be turned farther around upon the die-head, as described.

We are aware of Letters Patent granted 35 William Sellers, December 1, 1857, No. 18,775; of Letters Patent to L. W. Stockwell, February 20, 1872, No. 123,951, and of Letters Patent to Peace and Cox, July 29, 1873, No. 141,234, and

we lay no claim to the devices therein shown and described.

We claim—

1. In a pipe cutter and threader having a fixed die-head provided with radial die-slots, sliding dies arranged in the radial die-slots, and provided with lateral pins or studs for 45 engaging cam-grooves in the face-plate, the integral detachable combined face-plate and cam-ring provided with cams c on the inner surface of the cam-ring, radial slots c⁴ there-through, and cam-grooves c⁵ in the inner surface of the face-plate, constructed and adapted to operate substantially as specified. 50

2. In a pipe cutter and threader, the combination, with a die-head having radial sliding dies, of a rotating cam-ring having the 55 bracket c', the pivoted lever D, and the threaded rod d², provided with nut c³, substantially as and for the purposes specified.

3. In a pipe cutter and threader, the combination of a die-head having radial die-slots, 60 dies arranged in the radial slots of the die-head, a cam-ring having cams c, cam-slots c², and radial slots c⁴, which extend into the cam-slots, a projection, c⁵, on the cam-ring, and a swiveling stop, h³, on the frame which supports the die-head, substantially as and for 65 the purposes specified.

In testimony whereof we have affixed our signatures, in presence of two witnesses, this 23d day of November, 1883.

MOSES C. BIGNALL.
GEO. W. WHITMAN.
